US0D1047463S

(12) United States Design Patent (10) Patent No.: US D1,047,463 S
(45) Date of Patent: * Oct. 22, 2024

(54) FABRIC WITH PATTERN

(71) Applicant: Ningbo Mizhihe Import & Export Co., Ltd., Zhejiang (CN)

(72) Inventor: Wenchang Hu, Ningbo (CN)

(73) Assignee: Ningbo Mizhine Import & Export Co., Ltd., Zhejiang (CN)

() Term: 15 Years

(21) Appl. No.: 29/752,296

(22) Filed: Sep. 25, 2020

(51) LOC (14) Cl. 05-05

(52) U.S. Cl.

USPC D5/57; D5/60

(58) Field of Classification Search

USPC D5/8, 16, 24, 37, 43, 47, 53, 55, 56, 57,
